UNITED STATES PATENT OFFICE

HARVEY GILES, OF BROOKLYN, NEW YORK, ASSIGNOR TO ARTEMAS WARD, INC., OF NEW YORK, N. Y., A CORPORATION OF NEW YORK

COIN-CONTROLLED VENDING MACHINE

Application filed July 14, 1925. Serial No. 43,489.

The invention relates to an improvement in vending machines of the type which delivers an article, such as a piece of gum, a small carton of confection, or a like article, upon the insertion of a genuine coin of the proper denomination in the machine and the manipulation of the usual handle which actuates the article delivering means.

The general object of the invention is to reorganize and simplify the operating parts of a vending machine of the above type, in order to produce a more efficient machine having increased holding capacity with fewer operating parts. To this end one of the features of the invention is the provision of means whereby a single reciprocable bar or plunger is employed for delivering the articles from a plurality of vertically arranged hoppers or compartments. This plunger bar is arranged to operate in substantially the vertical plane occupied by the series of columns of articles and is provided with as many articles delivering fingers as there are hoppers or columns of articles, each finger corresponding to a hopper and arranged to remove and deliver the articles from its hopper. The arrangement is such that each column of articles is completely exhausted, beginning with the rear column, before the articles are delivered from the preceding columns, except that the original lowermost article in each preceding column is delivered before the lowermost article in the last column is delivered. A feature of the invention incidental to the foregoing feature is the provision of means whereby the delivery of the articles from the succeeding hoppers is not interfered with by the articles in the preceding hopper or hoppers.

Another feature of the invention is to so construct and arrange the coin slot that after the coin has been effectively used by the operating parts of the article delivering mechanism of the vending machine, it is caused to fall in a plane at right angles to the plane in which it enters the machine. By changing the plane in which the coin falls, a coin box of increased capacity may be employed and means arranged for gradually and progressively filling the coin box so that the coins

therein will not interfere with the operation of the machine so long as there remain any undelivered articles in the machine. Another feature of the invention is the provision of novel means for detecting washers or slugs with a hole in their centers and preventing them from entering the machine. A further feature of the invention is the provision of a stop finger located in the last column of goods to be delivered, which stop finger comes into operation when the last article has been delivered to prevent the reciprocation of the plunger bar and the insertion of further coins in the machine. Still another feature of the invention is the provision of novel means for securing the operating parts of the machine in the cabinet. Other features of the invention will appear as the description proceeds, the advantages of which will be apparent to those skilled in the art. The invention itself consists in the improved vending machine hereinafter described and particularly pointed out in the appended claims.

In the accompanying drawings illustrating the preferred form of the invention:

Fig. 1 is a side elevation of a stand adapted to rotatably support three of the improved vending machines, a part of the figure being shown in section taken on the line 1—1 of Fig. 2;

Fig. 2 is a top plan of the parts shown in Fig. 1, with a portion of the figure shown in section;

Fig. 3 is a front vertical section taken along the line 3—3 of Fig. 12, looking in the direction of the arrows;

Fig. 4 is a rear elevation of the operating parts of the vending machine, with the cabinet and coin box shown in section;

Fig. 5 is a vertical section taken along the line 5—5 of Fig. 12;

Fig. 6 is a transverse vertical section taken along the line 6—6 of Fig. 8;

Fig. 7 is a front vertical section of the right hand side of the vending machine, taken along the line 7—7 of Fig. 6;

Fig. 8 is a view similar to Fig. 7, showing the positions of the parts of the operating mechanism after a coin has been deposited in

the machine and the handle depressed a part of the way;

Fig. 9 is a section taken along the line 9—9 of Fig. 10, the view being substantially the same as that shown in Fig. 8, with the parts in the positions they have at the completion of the downward stroke of the handle;

Fig. 10 is a section taken along the line 10—10 of Fig. 9;

Fig. 11 is a section taken along the line 11—11 of Fig. 4, looking in the direction of the arrows;

Fig. 13 is a section taken along the line 13—13 of Fig. 4;

Fig. 14 is a section taken along the line 14—14 of Fig. 8;

Fig. 15 is a section taken along the line 15—15 of Fig. 7;

Fig. 16 is a side elevation of the device for detecting and holding a washer;

Fig. 17 is an end elevation of the parts shown in Fig. 16;

Fig. 18 is a front elevation, partly in section, of the bottom part of the machine, showing particularly the positions of the parts in delivering the last article from the machine;

Fig. 19 is a section taken along the line 19—19 of Fig. 20, the figure being the left hand end of the parts shown in Fig. 18, and

Fig. 20 is a section taken along the line 20—20 of Fig. 19.

The improved vending machine as illustrated in the accompanying drawings comprises a plurality of upright hoppers arranged in series one behind another for containing the articles to be vended and a coin controlled mechanism by the manipulation of which an article is delivered. There may be any desired number of hoppers, and in the machine illustrated there are three, designated at 21, 22 and 23. Each hopper or compartment is adapted to contain a column of the articles 24 to be vended. These articles may be either packets or cartons of gum or candy, or they may be articles of a different nature, but substantially of the same shape.

The articles 24 as shown are of rectangular shape, and the operating mechanism of the vending machine is arranged to deliver the articles endwise from the machine. For this purpose the articles are arranged in the upright hoppers or compartments with their longitudinal axes coincident with the direction in which they are delivered from the machine.

The series of hoppers or compartments and the operating mechanism for delivering the articles are enclosed in a rectangular cabinet having a front end wall 26, a rear end wall 27, a side wall 28 and a door 29 pivoted by means of the rod 30 to the bottom 31 of the cabinet. The right hand end of the rod

30 is offset at 32 and enters the lower end of the rear end wall 27. A cotter pin 33 prevents the removal of the hinge or pivot rod 30 from the outside of the cabinet. The upper end of the cabinet is closed by the top 34, to which the door is fastened by the lock 18 secured to the inner side of the upper part of the door 29. In the lower part of the front end wall 26 is located an opening or discharge orifice 35 through which the articles are delivered. The articles are delivered onto a platform 36 having a depending flange secured to the wall 26. The opening or orifice above the platform 36 is protected by a guard 37 also secured to the wall 26. A pivotally mounted spring-pressed flap 25 prevents ingress into the machine beyond the opening 35. The rear end wall 27 is provided with a slot 17 through which projects the handle 38 of the mechanism by which an article is delivered.

Each hopper consists of a front end wall 40, a rear end wall 41, a side wall 42 and a side wall 43. The upright hopper or compartment thus constituted is open at its upper end and also at its lower end, and in addition the side wall 43 is provided throughout its middle section with an opening 44 which affords ready access to the interior of the hopper and permits the articles to be easily placed in or removed from the hopper. The upper ends of the side walls 42 of the hoppers are secured to a plate 45 by which they are held together. The left hand 46 of the plate 45 projects laterally beyond the upper end of the first hopper 21 to engage with a stud 47 projecting inwardly into the cabinet from the front end wall 26. This arrangement permits the attendant to tilt the series of hoppers forward when he is refilling them with articles. In each hopper is a weight 48 adapted to rest on the column of articles in the hopper. Each weight 48 is grooved longitudinally at 63 in its bottom side.

Located under the lower open ends of the hoppers and extending parallelly with the series of hoppers is a plate 49 adapted to support the columns of articles in the hoppers and along which the articles are adapted to be advanced when they are delivered from the machine. The plate 49 is spaced from the open lower ends 50 of the hoppers a distance equal to substantially the thickness of one and one-half articles and occupies the same plane as the delivering platform 36, so that when a coin has been deposited in the machine and the handle 38 has been manipulated the article nearest the opening 35 is pushed into position on the platform 36 to be removed by the purchaser. The plate 49 is provided with upright side walls 51 and 52 which embrace the lower ends of the side walls 42 and 43 of the hoppers. The plate 49 with its upwardly projecting sides 51 and 52

thus constitutes a trough into which the hoppers discharge the articles they contain.

Projecting laterally from the side wall 51 of the plate 49 are two hooks 53 adapted to engage a plate 54 which supports both the hoppers and the operating mechanism of the vending machine. This plate 54 is clearly shown in Figs. 4 and 5, in which it is seen that it consists of a lower part 55 extending entirely across the cabinet, an upright middle arm 56 having an offset lateral arm 57, and an upright end arm 58. These various parts of the plate 54 are provided with headed studs 59 adapted to project through the holes 60 in the side wall 28 of the cabinet. The holes 60 are provided with neck portions 61 adapted to receive and hold the studs 59. The arrangement is such that when the heads 62 of the studs 59 are inserted through the holes 60 the plate descends until the studs 59 rest in the bottoms of the neck portions 61. The plate 54 is then held against accidental displacement by means of a spring pressed latch 64 pivotally mounted in the wall 28 of the cabinet. The latch 64 is adapted to engage with the stud in the end of the offset arm 57 of the plate 54. The plate 54 is held spaced from the wall 28 of the cabinet by means of the washers 65, in order that the three arm bell crank lever 66 of the operating mechanism pivoted on the upper end of the arm 56 may be located and function between the plate 54 and the wall 28 of the cabinet.

When the articles are placed as columns in the upright hoppers, the lowermost article in each column rests on the plate 49. The article delivery mechanism of the present invention is so constructed and arranged that only the lowermost articles of the columns of articles in hoppers 21 and 22 are delivered from the machine before the articles are entirely delivered from hopper 23. If, in Fig. 3, it is assumed that the article 67 was the lowermost article in the hopper 21, that the article 68 was the lowermost article in the hopper 22 and that the article 69 was the lowermost article in the hopper 23, it is clear that articles 67 and 68 will be delivered before article 69. Thereafter, however, all the articles in hopper 23 will be delivered from the machine before any of the remaining articles in hoppers 21 and 22 are delivered, the articles from hopper 23 passing under the lowermost articles in hoppers 21 and 22. Means are provided to prevent the lowermost articles in hoppers 21 and 22 from interfering with the travel of the articles along the plate 29.

After all the articles originally contained in hopper 23 have been delivered, then the articles contained in hopper 22 are delivered in the same manner, namely, under the articles contained in hopper 21; and lastly, the articles contained in hopper 21 are delivered.

It will be understood that this is the mode

of operation of delivering the articles from the machine, irrespective of the number of hoppers. Inasmuch as the lowermost article in each hopper rests on the plate 49 when the articles are inserted in the hoppers, it will be understood of course that these articles must be delivered before the articles in the last hopper are delivered. After the articles originally resting on the plate 49 have been delivered, the hoppers are exhausted in turn, beginning with the rearmost hopper, so that the top article in the first hopper, for example, article 70 in hopper 21, is the last article to be delivered from the machine.

The mechanism by which this mode of operation is accomplished comprises a series of pusher fingers 72, 73 and 74, there being as many pusher fingers as there are hoppers. Each pusher finger corresponds to a hopper and is adapted to deliver the articles in that hopper from the machine, except that the articles originally resting on the plate 49 are delivered by the rearmost finger, namely, the finger 74. The pusher fingers are pivotally mounted on a plunger bar 77, which is in the form of an inverted U and comprises the side walls 76 and 81 and cross pieces 83. The plunger bar 77 is provided with two screws 78 (Fig. 5) which project through a slot 79 cut longitudinally in the lower portion 55 of the plate 54. The screws 78 are loosely received in the slot 79 so that the plunger bar may reciprocate freely, and the screws 78 are provided with enlarged heads so that the plunger bar may be supported in position and operate without cramping. The side wall 81 of the plunger bar is turned inwardly at its lower end to rest on the inturned flange 82 of the plate 54. This arrangement aids in supporting the plunger bar and facilitating its operation.

The upper article-engaging end 84 of each pusher finger is arranged to project through and to reciprocate in a longitudinal slot 85 in the plate 49. The lower ends of the plunger fingers are weighted so that the fingers tend to turn in a clockwise direction. The stops 86 projecting laterally from the bottom of the side 76 of the plunger bar 77 determine the operative positions of the article-engaging ends of the fingers. The arrangement is such that when the plunger bar 77 is in retracted position at the right hand side of the cabinet only the plunger finger corresponding to the last column of articles is in effective article delivering position, the preceding fingers being held depressed and inoperative by the articles on the plate 49, as shown in Fig. 3. In this figure, however, the fingers are shown in article delivering position. It will be readily understood that when the plunger bar is moved to the right, the finger 74 will assume an effective delivering position behind the lowermost article 89 in the hopper 23. It will thus be understood that

as each column of articles becomes exhausted the pusher finger corresponding to that column becomes inoperative, whereas the next preceding finger comes into play. This is the mode of operation regardless of the number of columns of articles to be delivered.

In order to prevent articles in the hoppers preceding the hopper from which the articles are being delivered from interfering with the travel of articles along the plate 49, each hopper preceding the last one is provided with a hinged deflector plate which may conveniently be attached to the lower edge of the front end wall 40 of the succeeding hopper. Thus the deflector plate 91 for the hopper 42 is attached to the lower edge of the front end wall 40 of the hopper 23 and the deflector plate 92 for the hopper 21 is attached to the lower edge of the front end wall 40 of the hopper 22. The deflector plate 92 of the hopper 21, as shown in Fig. 3, clearly illustrates the mode of operation of these plates and how they prevent the articles in the preceding hoppers from interfering with the travel of the articles along the plate 49. Each deflector plate is recessed in its bottom edge to accommodate and permit the free passage of the article-engaging ends 84 of the pusher fingers.

The mechanism for actuating the plunger bar 77 to cause the pusher fingers to deliver an article from the machine upon the insertion of a coin therein and the manipulation of the handle 38, comprises the three arm lever 66 and the means for operating it. The lower end of the arm 94 of the lever 66 is slotted to loosely receive a screw 95 which passes through the slot 79 and is fixed in the wall 81 of the plunger bar 77. The lateral arm 97 of the lever 66 is provided at its free end with the pin 98 which projects through and is loosely engaged by a slot 99 in a vertically reciprocatable plate 100 from which the handle part 38 projects through the vertical slot 17 in the rear end wall 27 of the cabinet. The plate 100 is arranged to reciprocate vertically on the upright part 58 of the plate 54. The outline of the plate 100 is clearly indicated in Figs. 7, 8 and 9. It is held in operative position on the part 58 by the flat headed screws 101 and 102 which project loosely through the vertically arranged slots 103 and 104 respectively. The plate 100 is normally retracted upwardly to its inoperative position by means of a contraction spring 106, the upper end of which is secured to a pin 107 fixed in the wall 28 of the cabinet and the lower end of which is secured to a pin 108 fixed in the upper end of the plate 100. When a coin of proper denomination has been inserted into the mechanism (as will be presently explained) the handle 38 may be depressed to move the plate 100 to the full limit of its downward movement and thereby cause the arm 94 of the lever 66 to move

the plunger bar 77 and the pusher fingers from their right hand retracted position to the left hand (as shown in Fig. 3), thereby delivering an article. As the lever 66 oscillates during the manipulation of the handle 38 the pin 98 travels in the arcuate slot 110 in the upright part 58 of the plate 54.

The coin slot by which a coin is so positioned that the operating mechanism may be effective in delivering an article from the machine comprises an upper section generally indicated at 111 (Fig. 4) and a lower section generally indicated at 112. The upper part or section 111 of the coin slot is arranged transversely of the cabinet and the lower part or section 112 of the coin slot is arranged substantially at right angles with the upper part. The upper part 111 of the coin slot is formed by a plate 114 secured to a plate 115 which in turn is secured to a flange 116 offset inwardly from the upright part 58 of the plate 54. The side edges 117 of the plate 114 are bent inwardly to form a slot, the inner edges of the sides 117 being spaced apart to permit the dog 118 to travel between them to engage with a coin. The dog 118 is pivotally mounted on a bracket 113 secured to the plate 100 and its lower hook-like end 119 is yieldingly pressed towards the coin slot by a spring 120. A guard 123 (Fig. 4) fixed to the plate 100 covers the dog 118 and spring 120. When the plate 100 is in retracted position, as shown in Fig. 7, the upper part 121 of the coin slot holds the dog 118 outwardly to permit the coin 122 to enter fully into the slot and encounter the inturned end 125 of a coin gage 124 by which a genuine coin of requisite thickness is stopped and held so that the dog may engage therewith and make it effective in delivering an article. If the coin or other disk of metal is too thin it will pass the gage 124 and so, ineffectively through the coin slot. This coin gage 124 is of usual construction and mode of operation.

If the handle 38 is depressed when there is no coin in the coin slot held in position by the inturned end 125 of the coin gage 124, the hook part 119 of the dog 118 will encounter the stop 126 and thereupon the descent of the plate 100 and the actuation of the plunger bar 77 will be arrested.

The means for directing a genuine coin into the upper part 111 of the coin slot consists of an obliquely arranged plate 128 pivotally mounted at 129 on the upper end of the upright part 58 of the plate 54. Cooperating with the plate 128 is a dog 130 pivotally mounted at 131 on a plate 132 offset at right angles from the upper end of the plate 100. The dog 130 is so shaped that it tends to turn in a counter-clockwise direction and bring the nose portion 134 thereof against the surface of the plate 128. The entrance 136 of the coin slot is located in the cover 130

part 29 of the machine and is arranged to deliver the coin against the upper surface of the plate 128 and just above the nose 134 of the dog 130 so that it will descend between the dog and the plate 128 into the upper part 111 of the coin slot. If a disk of fibreboard or other relatively light material is inserted through the entrance 136 it will be caught and held by the dog 130. Then as the plate 128 is swung outwardly, when the handle 38 is depressed, by the travel of the pin 138 fixed in the upper end of the plate 100 in the slot 139 formed in the member 140 connected with the plate 128, the disk of fibreboard or the like will be deflected from the entrance 142 of the upper part of the coin slot. If a disk of iron is inserted through the entrance 136 it will be caught and held on the plate 128 by means of the usual magnet 143 secured to the underside of the plate 128 and projecting downwardly below it. Then when the handle 38 is depressed and the plate 128 is swung outwardly the slug will drop to the bottom of the machine ineffectively.

To prevent the insertion of a washer into the coin slot the entrance 136 thereto is provided with means for detecting and holding the washer. On the inner side of the door 29 is located a plate 145 having a vertical slot 146 in alignment with the entrance 136. A latch 147 pivoted at 148 in the plate 145 is arranged across the upper end of the slot 146. A spring 149 tends to press the latch 147 against the stop pin 150. A stop finger 152 pivoted at 153 in the plate 145 is arranged to be moved across the middle of the slot 146 when a washer is pushed into the entrance 136 and the slot 146 far enough to move the latch 147. The connection between the stop finger 152 and the latch 147 consists of a flexible member 154 fixed in the stop finger and loosely connected with the latch. This construction is provided to permit the latch 147 to be pushed aside when the stop finger 152 encounters the solid center of a genuine coin.

When a washer has been inserted into the entrance 136 and encounters the latch 147 the stop finger 152 is moved through the center of a washer and across the middle of the slot 146. The front side 156 of the stop finger is flat, as shown in Fig. 17, so as to prevent the user of the washer from pushing it through the entrance and into the machine. The rear side 157 of the finger, however, is beveled to permit the retraction of the washer without unfastening the door 29 or otherwise dismantling the machine.

Inasmuch as the arrangement of the hoppers one behind another in series, as set forth above, gives an increased article holding capacity in a relatively small cabinet, it is necessary to provide a coin box of such construction and arrangement that it will contain the increased number of coins without interfer-

ing with the working of the operating mechanism of the machine. For this purpose the coin box 160, which is substantially square in cross-section, extends throughout almost the full width of the cabinet and is supported on the bottom 31 thereof below the plunger bar 77. The right hand end of the coin box 160, viewing Fig. 4, is located under the lower part 112 of the coin slot. In the right hand end of the coin box is an inclined surface 161 located immediately under the discharge opening 162 of the coin slot so that when the coins fall from the coin slot they will strike the inclined surface 161 and roll toward the other end 163 of the coin box, thereby progressively filling the coin box. By this arrangement the hoppers may be completely exhausted of their contents without liability of the coins piling up in the right hand end of the coin box and interfering with the actuation of the plunger bar.

The lower part 112 of the coin slot consists of an inclined plate 165 (Fig. 10) supported from the right hand end of the part 55 of the plate 54. The right hand edge 166 of the plate 165 is folded over parallelly therewith so as to constitute an inclined slot by which the coins are directed into the coin box. The other edge 167 of the plate 165 projects forwardly and constitutes a lower extension of the upper part 111 of the coin slot. In order to deflect the coins from the upper part 111 of the coin slot which is arranged transversely of the longitudinal axis of the coin box 160, into the lower part 112 of the coin slot which is arranged parallelly with the longitudinal axis of the coin box, the lower end of the upper part 111 of the coin slot is provided with a deflector plate 168 which projects inwardly and downwardly into the upper end of the lower part 112 of the coin slot.

By reference to Figs. 10 and 11 it will be seen that the coin box 160 is located to one side of the hinge 30 thereby leaving a space 170 between the wall 171 of the coin box and the door 29. To prevent the coins sliding down the inclined plate 165 of the lower end of the coin slot from entering the space 170, an inclined guard plate 172 secured to the inner side of the door 29 and located under the lower end of the plate 165 is provided to deflect the coins into the coin box 160.

When the last article 70 of the column of articles in the first hopper 21 has been delivered, the plunger bar 77 is prevented from returning to its retracted position, thereby holding the seal 174 in front of the entrance 136 to prevent the insertion of more coins into the machine. The seal 174 for the entrance 136 of the coin slot is a plate mounted on the vertical edge of the plate 132 carried by the slotted member 140. The means for holding the plunger bar 77 at the left hand side of the machine and the seal 174 behind

the entrance 136 of the coin slot when the last article has been delivered from the machine, consists of a hook 175 pivotally mounted in a slot 176 cut longitudinally in the weight 48 located in the first hopper 21. 5 The hook 175 is held inoperative by the article 70. When this article has been delivered, however, the hook 175 descends through the notch 173 in the plate 49, as shown in Fig. 18, and positions itself to the rear of the cross piece 177 of the plunger bar 77. Then when the handle 38 is released by the purchaser the rearward movement of the plunger 77 brings the cross piece 177 into engagement 15 with the hook 175, thereby holding the plunger bar 77 stationary and the seal 174 behind the entrance 136 to the coin slot.

The operation of the improved vending machine may be briefly recapitulated as follows: When the parts are in normal inoperative position, the plunger bar 77 is at the right hand side of the cabinet, as shown in Fig. 4, and the handle 38 is at the upper end of the slot 17 in the rear end 27 of the cabinet. 20 If now someone attempts to depress the handle 38 without inserting a coin into the machine, the dog 118 will engage with the stop 126 and prevent the effective actuation of the plunger bar 77. When a genuine coin has been pushed into the entrance 136 and 25 slides down the inclined plate 128 into the upper part 111 of the coin slot it encounters the offset end 125 of the coin gage 124, and is held in the position shown in Fig. 7. It will be observed that the coin acts as a guard to prevent the hook portion 119 of the dog 118 from encountering the stop 126. Upon 30 the depression of the handle 38 after the insertion of a genuine coin into the coin slot, the spring 120 forces the hook 119 of the dog 118 into engagement with the coin, as shown in Fig. 8, thereby permitting the full downward movement of the plate 100 and the actuation of the plunger bar 77 to cause an article to be delivered in the manner described above. If the purchaser should depress the handle 38 only part way after inserting a coin in the machine the dog 178 35 will engage with one or the other of the teeth 179 of the arm 180 of the three armed lever 66 and prevent the return of the handle 38 to its normal position. The dog 178 is pivotally mounted at 181 on the offset arm 57 of the plate 54 and is held in its normal 40 position by means of a spring 183. The arrangement of the dog 178 with relation to the teeth 179 and the end of the arm 180 is such that the handle 38 must be completely depressed so that the lower corner 184 of the arm 180 will pass beyond the dog 178 before 45 the handle 38 will return to its normal position in the upper end of the slot 117. As each column of articles is delivered the pusher finger corresponding thereto becomes 50 inoperative and the next preceding finger be-

comes effective to deliver the articles from the machine. When the last article in the first column has been delivered the hook 175 drops down behind the cross piece 177 on the forward end of the plunger bar 77 and thereby holds the bar in its forward position and the seal 174 behind the entrance 136 of the coin slot to prevent the insertion of further coins into the machine. 70

The improved vending machine may be placed on a stationary stand or against a wall, as is usual. Its compactness, however, due to its increased capacity, adapts it to be placed on a revolving, portable stand, as illustrated in Figs. 1 and 2. This stand may support any desired number of the vending machines. In the stand illustrated there are three machines, designated 190, 191 and 192. The stand comprises an upright shaft 193 supported by ball-bearings 194 in the upper part of a base 195. To the upper end of the shaft 193 a handle 196 is fixed by which the stand and its machines may be moved from place to place. The cabinets of the vending machines are supported from the three-armed plates 197 and 198 fixed to the upper and lower ends of the shaft 193. The ends of the arms of the plates 197 and 198 are down turned as flanges 199 and to these flanges the walls 28 of the cabinets are secured by the bolts 200. 80

What I claim as my invention and desire to secure by Letters-Patent, is:

1. A vending machine having, in combination, a plurality of upright hoppers having open lower ends arranged one behind another in series, each hopper being adapted to contain a column of articles to be vended, a trough into which the hoppers discharge, said trough being provided with a longitudinal slot in its bottom, a bar located beneath the trough and arranged to reciprocate parallelly with the slot, a series of fingers pivoted on the bar, there being as many fingers as hoppers, the upper article-engaging ends of the fingers being arranged to project through the slot in the bottom of the trough, each finger being positioned to the rear of its corresponding hopper when the bar is in retracted position, and mechanism including a lever and vertically movable handle for actuating the bar, said mechanism being disposed behind the hoppers, and the lever and handle being movable in a plane substantially parallel with that of the common plane of the hoppers. 100

2. A vending machine having, in combination, a series of upright hoppers arranged in substantially the same vertical plane, each hopper being adapted to contain a column of articles to be vended, a bar located under the hoppers and arranged to reciprocate longitudinally of the series of hoppers, a series of movable fingers corresponding to the columns mounted on the bar, each finger occupying a position behind its column when the bar is in retracted position, and means including a 110

lever and handle movable in a plane parallel to that of the common plane of the hoppers for actuating the plunger bar to deliver an article upon the complete manipulation of the handle, the preceding fingers riding inoperatively under their columns until the succeeding columns of articles are exhausted.

3. A vending machine having, in combination, a series of upright hoppers arranged in substantially the same vertical plane, each hopper being adapted to contain a column of articles to be vended, a bar located under the hoppers and arranged to reciprocate longitudinally in the common plane of the series of hoppers, a series of movable fingers mounted on the bar and arranged, unless depressed, to project upwardly behind the lowermost article in the corresponding hopper when the bar is in retracted position, the columns of articles preceding the last unexhausted column acting to depress and render inoperative their respective fingers, the finger corresponding to the last or rearmost unexhausted column acting to deliver the articles from that column beneath the preceding columns, and means including a lever and a handle behind the common plane of the hoppers for actuating the bar.

4. A vending machine having, in combination, a hopper for containing the articles to be vended, coin controlled mechanism for delivering an article from the hopper, a plate on which the coin controlled mechanism is supported, headed studs fixed in the plate, a cabinet for enclosing the hopper and the mechanism and having holes in the rear side thereof, each hole being provided with a neck to receive and support the studs, and a latch for holding the plate in position.

5. A vending machine having, in combination, a hopper for containing the articles to be vended, coin controlled mechanism for delivering an article from the hopper, a plate on which the coin controlled mechanism is supported, headed studs fixed in the plate, a cabinet for enclosing the hopper and the mechanism and having holes in the rear side thereof, each hole being provided with a neck to receive and support the studs, and a spring actuated latch cooperating with one of the headed studs for holding the plate in position.

6. A vending machine having in combination a hopper for containing articles to be vended, coin controlled means for removing an article from the hopper, a cabinet for enclosing the hopper and the coin controlled mechanism, a plate for supporting the mechanism, headed studs secured to the plate, the rear wall of the cabinet being provided with holes through which the heads of the studs are adapted to pass, the holes having neck portions for receiving and supporting the studs, and yieldable means for anchoring the plate in position.

7. In a vending machine of the class de-

scribed, a casing having a delivery opening in one of its sides, an upright hopper within the casing for containing articles to be vended, the lower end of said hopper being adjacent to said delivery opening, reciprocable means below the hopper for ejecting the lowermost article from the hopper laterally through the delivery opening, and means including a lever and a substantially vertically movable handle for actuating said reciprocable means, said lever being disposed behind the hopper and being adapted to swing in a plane close to and parallel with the back wall of the hopper.

8. A machine comprising a commodity chamber containing front and rear stacks of articles, and a coin controlled device for delivering said articles comprising means for advancing an article from the rear stack to the front stack at the same time that an article from the front stack is being delivered and means active only after the rear stack is empty for delivering articles from the front stack.

9. In a vending machine, a coin controlled mechanism for multiple stacks of articles to be dispensed comprising a carrier adapted to become operative upon the insertion of a coin, a pusher for advancing an article from one stack to another and for delivering an article from one stack, and a supplemental pusher for delivering an article after one stack has become exhausted.

10. In a vending machine containing front and rear stacks of articles to be dispensed, a coin controlled delivering mechanism comprising a sliding carrier, an ejector mounted upon the rear of said carrier and adapted to be tripped into active position upon the insertion of a coin to eject articles from the machine, and a supplemental ejector on the forward portion of the carrier operable to eject articles from the machine when one of the stacks is empty.

11. In a vending machine having a commodity chamber, a coin controlled mechanism having an ejector actuated by the insertion of a coin, means for locking said ejector against movement when no articles are present in the commodity chamber, said means comprising an element of which one end projects into the commodity chamber and the other end of which projects into the path of the ejector.

12. In a vending machine, a casing having a bottom upon which front and rear stacks of articles are adapted to rest, a coin controlled discharge carrier, means on the carrier for discharging the lowermost article in the front stack and for advancing the lowermost article of the rear stack, and additional means for delivering the lowermost article of the front stack when the rear stack is exhausted.

13. A vending machine comprising in combination a compartment for front and rear

stacks of articles, means operable upon the introduction of a coin for dispensing said articles comprising a plurality of ejectors, one of said ejectors being adapted to advance an article from the rear stack to the front stack and at the same time deliver an article from the front stack, and the other of said ejectors adapted to deliver articles from the front stack when there are no articles in the rear stack.

14. A coin controlled machine comprising a casing having a plurality of stacks of articles, means adapted to dispense the bottommost article of one stack by abutting against it the bottommost article of the next stack, and additional means adapted to dispense the remaining articles in the machine after one of the stacks has been depleted, and means to prevent operation of the machine by spurious coins of insufficient size or weight.

In testimony whereof I hereunto affix my signature.

HARVEY GILES.
